WELL SWAB

Benjamin E. Parrish, Dallas, Tex.

Application February 27, 1937, Serial No. 128,847

21 Claims. (Cl. 103—225)

This invention relates to new and useful improvements in well swabs.

This application is filed as an improvement on the well swab disclosed in my co-pending application, filed July 22, 1935, Serial Number 32,561.

One object of the invention is to provide an improved swab having all of the advantages of the swab disclosed in my co-pending application and which is particularly adapted for use in oil wells, being constructed so as to descend rapidly in the well fluid, whereby the swab may be "run" in a minimum amount of time.

An important object of the invention is to provide an improved swab wherein the packing element is constructed in sections arranged to be displaced out of horizontal alignment with each other so that the fluid may by-pass said element, the displacement being automatic on the down-stroke; said sections being mounted on a supporting mandrel, whereby said mandrel not only serves as a support for the packing element but also acts as a guide during the displacement of the sections, thereby eliminating an auxiliary guide means and making for a more simple and stronger structure.

Another object of the invention is to provide an improved well swab wherein the packing element is constructed in units, which are moveable with relation to each other, each unit including one section of the annular elastic packing member, with improved means for securing the section in its unit, whereby the section is rigidly held in place without materially weakening said section and also whereby the same may be readily removed for replacement, or other purposes.

A further object of the invention is to provide an improved well swab having a split elastic packing element with one half of said element arranged to undergo vertical movement with relation to the other half, and improved means for limiting the distortion of the packing whereby distortion of the packing element beyond its elastic limits is prevented.

Still another object of the invention is to provide an improved swab wherein the packing element is constructed in units, the parts of the various units being interchangeable with each other, whereby manufacturing costs are minimized and assembly of the device greatly simplified.

A still further object of the invention is to provide an improved swab wherein all valves, balls, seats, etc., are eliminated and wherein the size of the fluid by-pass may be readily adjusted to control the speed at which the swab descends

through fluid in the well casing or tubing; the assembly being simple in manufacture and arranged to be attached to any suitable lowering rod, cable or device.

A construction designed to carry out the invention will be hereinafter described together with other features of the invention.

The invention will be more readily understood from a reading of the following specification and by reference to the accompanying drawings, in which an example of the invention is shown, and wherein:

Figure 1 is an elevation of a swab constructed in accordance with the invention, and showing the packing element in its packing position.

Figure 2 is a view similar to Figure 1 and showing the sections of the packing element if placed vertically from each other.

Figure 3 is an elevation taken at right angle to Figure 1.

Figure 4 is an elevation taken at right angle to Figure 2.

Figure 5 is a transverse, vertical sectional view of the swab, taken on the line 5—5 of Figure 3 and showing the mandrel in elevation.

Figure 6 is a view similar to Figure 5 taken on the line 6—6 of Figure 4.

Figure 7 is an isometric view of the supporting mandrel.

Figure 8 is a perspective view showing the elements of each section or unit of the packing member separated from each other.

Figure 9 is a horizontal, cross-sectional view, taken on the line 9—9 of Figure 1.

Figure 10 is a horizontal, cross-sectional view, taken on the line 10—10 of Figure 1, and

Figure 11 is a horizontal, cross-sectional view, taken on the line 11—11 of Figure 2.

In the drawings, the numeral 10 designates a mandrel which is preferably made of a solid piece of metal, or other suitable material. The mandrel is substantially cylindrical in cross-sections and has its upper end provided with screw threads 11, whereby a box 12 may be screwed thereon.

The box is provided with an upwardly extending integral nipple 13, which is of such size as to receive the standard threaded box (not shown) at the lower end of the usual sucker rod, whereby the mandrel may be readily connected to said rod and lowered into the well casing A.

It is pointed out that the box 12 may be readily removed and a similar box having a nipple of a different diameter may be substituted therefor, whereby the mandrel could be lowered by means of a pipe or cable instead of a sucker rod. With such ar-

angement specially designed couplings are unnecessary and the mandrel may be connected with any of the usual lowering devices.

The lower end of the mandrel 10 is provided with screw thread 14, whereby a plug 15 may be attached to the lower end of the mandrel. The plug preferably has its lower end rounded so that as the mandrel is lowered into the fluid, such lowering is facilitated by this rounded portion.

10 Mounted on the mandrel 10 is a flexible or elastic packing element 16. The packing element is constructed of two halves or units B and C which are semi-circular in cross-section and are arranged to fit around the mandrel as clearly shown 15 in Figure 9. Both units of the packing element are exactly alike so that when they are positioned in horizontal alinement with each other they form an annular packing element. The unit B is slideable vertically throughout the length of the 20 mandrel 10, while the unit C is mounted in a fixed position at the lower end of said mandrel as will be explained. With this arrangement the unit B may be displaced vertically out of horizontal alinement with the other unit C.

25 Since each unit is exactly like the other, a description of one will suffice. Each unit includes an elastic or resilient packing member 17 which is substantially semi-circular in cross-section and which has its outer surface tapered inwardly at 30 its upper and lower ends, as is clearly shown in Figure 8. The upper end of the packing member is adapted to fit within the recess 18 of a thimble 19. The thimble is substantially semi-circular in cross-section and is arranged to snugly fit the outer surface of the cylindrical mandrel 10. The inner wall of the thimble 19 is extended downwardly to form a projecting skirt 20 which extends contiguous to the inner wall of the packing member when said member is in position within 35 the thimble. For fastening the upper end of the packing member within the recess 18 of said thimble, the packing element is formed with a radial opening 17' which is in alinement with an opening 21 which is formed in the inner wall of the thimble (Figure 5). The outer wall of the thimble is formed with a reduced opening 22, the inner end of which is enlarged to the diameter of the openings 17' and 21, whereby an internal annular shoulder 23 is formed in the outer wall of 40 said thimble. It is noted that the openings 21, 17' and 22 are in alinement with each other. After the upper end of the packing member 17 has been inserted into recess 18 of the thimble 19 and before the unit is placed around the mandrel, as will be explained, a pin 24 is inserted into 45 the opening from the inside of the thimble. This pin has a diameter of such size as to snugly fit in the openings 21 and 17' and into the enlarged portion of the opening 22. The extreme outer end of the pin is reduced as shown at 50 24' so as to fit within the reduced opening 22 in the outer wall of the thimble. The off-set or shoulder formed on the pin 24 abuts the internal annular shoulder 23 in the outer wall of the skirt, 55 whereby outward movement of the pin is prevented. When the unit is mounted on the mandrel 10, the inner end of the pin engages the outer surface of said mandrel, whereby inward displacement of the pin is prevented. When it 60 is desired to remove the pin, it is merely necessary to remove the unit from the mandrel and push the pin inwardly out of the opening. With such arrangement a most simple and effective retaining means is provided for holding the packing member in place within the thimble 19.

The lower end of the packing member 17 is inserted within the recess 25 of a thimble 26, which is similar in construction to the upper thimble 19. The lower end of the packing member is retained within the lower thimble by a pin 27, similar to the pin 24. It is noted that when the packing member is secured between the thimbles 19 and 26, the inner end of the skirt 20 of the upper thimble and the inner end of the lower skirt 28 of the thimble 26 are spaced 10 from each other. This position is clearly shown in Figure 5, and occurs when the packing member 17 is in its normal or undistorted position.

For slideably mounting the unit B on the mandrel 10 said mandrel is provided with a pair 15 of diametrically opposite grooves or keyways 29 which extend vertically throughout the length of the mandrel. Each thimble 19 and 26 is provided with inwardly projecting ribs or keys 30 which are located at the inner surface thereof. 20 The ribs or keys are adapted to slide within the grooves or recesses 29 in the mandrel and obviously, prevent displacement of the unit from said mandrel. In mounting the unit on said mandrel it is only necessary to remove the plug 15 at the 25 lower end thereof, and to slide the unit upwardly on the mandrel, whereby the keys 30 engage the groove. The plug is then returned to the lower end of the mandrel and it will be seen that the unit B is confined to a vertical movement between said plug and the socket 12 at the upper end of the mandrel.

The unit C is constructed exactly as is the unit B and is mounted on the mandrel 10 in a similar manner. However, the inwardly projecting ribs or keys 30 of the thimbles of the unit C engage in diametrically opposite slots or keyways 31. The length of the keyways 31 is less than the length of the keyways 29, being substantially the vertical length of the unit C. Thus the 40 grooves or keyways 31 extend from the lower end of the mandrel 10 to a point opposite the upper end of the unit C. It is noted that the keyways 31 extend contiguous to the keyways 29 and therefore the lower end of the latter are combined with the former to form a comparatively wide groove at the lower end of the mandrel. Since the keyways or grooves 31 terminate at the upper end of the unit C it will be seen that when said unit is mounted on the mandrel, the uppermost thimble 19 of the unit will abut the end of the groove 31. It will be held in this position by the engagement of the plug 15 with its lower end, whereby the unit C is mounted in a fixed position incapable of movement with relation to the 45 mandrel, on said mandrel. Since the grooves 29 within which the unit B is slideable extend throughout the length of the mandrel and it will be evident that this unit may slide vertically with relation to the unit C which is attached in a fixed 50 position on said mandrel.

In operation, the assembly is secured to a single pipe, sucker rod or other lowering device and lowered into the well casing A with the parts in the position shown in Figures 1, 3 and 5. As soon 55 as the assembly strikes the fluid within the well casing, the fluid pressure will immediately raise the unit B of the packing element on the mandrel 10, the vertical keys 30 on the thimbles of said unit sliding upwardly in the diametrically opposite grooves or keyways 29. The mandrel is of sufficient length so as to permit the unit B to move upwardly to the position shown in Figures 2, 4 and 6, with the lower end of the unit B opposite the upper end of the unit C.

The thimbles 19 and 26 of both units B and C are inclined inwardly toward their outer end and due to this inclination, it will be seen that an enlarged space D, as indicated in Figure 4, is provided between the units B and C when the former is in its raised position. This space permits the fluid to flow from beneath the assembly upwardly thereby and is substantially equal to the cross-sectional area of the casing A, whereby there is practically no resistance to the downward passage of the assembly in the well casing. The enlarged by-pass permits the assembly to be lowered rapidly and each "run" may be made in a minimum length of time. It is obvious that the displacement of the units of the packing assembly out of horizontal alignment with each other acts as a valve to permit by-passing of the fluid on the downstroke of the device.

When the assembly has reached its lowermost position and the raising operation has begun, the fluid pressure above the assembly will immediately act upon the raised unit B to lower the same. This unit will of course, immediately move downwardly on the mandrel until the lower end of its thimble 26 rests upon the plug 15 screwed on to the lower end of said mandrel. In this position, the unit B is opposite the stationary or fixed unit C and the fluid will then act upon both units to force the thimbles 19 thereof downwardly toward the lower thimble 26, whereby the resilient or elastic packing members 17 which are confined between said thimbles, are expanded into engagement with the inner wall of the well casing A. The upper thimble 19 will move downwardly until the inner edge of the skirts 20 which project downwardly therefrom, strike the inner edge of the upwardly projecting skirts 28 on the lower thimble 26. When this occurs, further distortion of the packing member 17 is prevented. Therefore, it will be seen that the extended skirts provided on the thimbles provide a positive means for preventing a distortion of the packing member 17 beyond the elastic limits of said members. The inner faces of the thimbles 19 and 26 of both units are machined so that when the two units are in horizontal alignment, a ground joint which prevents leakage is formed. Continued upward movement of the assembly after the packing members 17 have moved into engagement with the well casing A, will lift the fluid above the packing element and at the same time the well of the casing will be swabbed.

It is pointed out that when the swab is being lowered in the well casing and the unit B is in its raised position (Figure 4), there is a possibility that a stone, rock or other extraneous matter may become lodged in the space D between the lower thimble 26 of the unit B and the upper thimble 19 of the unit C. Due to the inclination of the outer wall of the thimble, it will be seen that should this occur, a downward movement of the upper unit C will provide a shearing or cutting action as the lower thimble of the unit C slides downwardly with relation to the upper thimble 26 and the unit C. This shearing action would remove any extraneous matter which might become lodged between the units and therefore any danger of such extraneous matter preventing the units from moving back into horizontal alignment upon the beginning of the upstroke is eliminated.

From the above, it will be seen that a swab wherein the packing element is utilized as a valve is provided. The structure is such that the entire assembly is made of a minimum number of

parts and may be quickly and easily attached to or detached from the mandrel. The removal of the plug 15 from the lower end of said mandrel will permit both the units B and C to be slid from the lower end of said mandrel. After the units are removed, it is only necessary to knock out the pins 24 and 27 to entirely disassemble each unit. This makes for easy replacement of the packing member 17.

Manufacturing is simplified and cost greatly reduced by forming diametrically opposite vertical grooves or keyways in the mandrel. These grooves not only serve as a positive guide means for the movement of the unit B but also provide a positive means for holding the unit on the mandrel. By so utilizing the grooves, it is not necessary to employ extraneous guide means for the unit B. The parts of each unit are interchangeable with the parts of all the other units and thus all the thimbles present in both units may be used on either one and either at the upper or lower end of each. The packing members 17 are exactly alike and can be mounted in either the unit B or the unit C. The interchangeability of the parts makes for easy assembling of the device as well as materially reducing the cost of manufacture. It is again noted that the by-pass D is of such size as to eliminate any great resistance in the downward travel of the assembly which makes for rapid lowering of the device in the well fluid present in the well casing A. The provision of the box 12 having the nipple 13, an integral part thereof, eliminates the necessity of providing special coupling, whereby the assembly may be lowered by any suitable lowering device now on the open market.

What I claim and desire to secure by Letters Patent is:

1. A well swab including, a mandrel having vertical grooves therein, a packing assembly mounted on the mandrel and including a pair of units which are arranged to be displaced out of horizontal alignment with each other to permit the well fluid to freely by-pass the assembly on the downstroke of the swab, and means on each unit for engaging the grooves of the mandrel for retaining said units on said mandrel.

2. A well swab including, a mandrel, a packing assembly mounted on the mandrel, said assembly including a stationary unit and a movable unit, said movable unit being arranged to be displaced vertically out of horizontal alignment with the stationary unit, and co-acting grooves and ribs on the mandrel and units for retaining the units in position on said mandrel.

3. A well swab including, a mandrel, a packing assembly mounted on the mandrel, said assembly including a stationary unit and a movable unit, said movable unit being arranged to be displaced vertically out of horizontal alignment with the stationary unit, and co-acting grooves and ribs on the mandrel and units for retaining the units in position on said mandrel, and for guiding the movable unit in its vertical movement.

4. A well swab including, a mandrel, a packing assembly carried by the mandrel and comprising a pair of units, the mandrel and units having co-acting grooves and ribs for retaining the units on said mandrel, and an elastic packing element constructed in two sections, one of which is mounted in one of the units which is stationary on the mandrel, the other section being carried by the other unit which is movable vertically on the mandrel, whereby the latter packing section may be displaced vertically with relation

to the other section to provide an enlarged space to permit the well fluid to by-pass the packing element freely on the downstroke of the swab.

5. A well swab including, a mandrel, a packing assembly mounted on the mandrel, said assembly including a stationary unit and a movable unit, said movable unit being arranged to be displaced vertically out of horizontal alignment with the stationary unit to permit the well fluid to freely by-pass the assembly on the downstroke of the swab, the movable unit being arranged to move back into horizontal alignment with the stationary member and to be distorted into packing position with said stationary member upon the upstroke of the swab, and co-acting grooves and ribs on the mandrel and units for retaining the units in place on said mandrel.

6. A well swab including, a mandrel, a packing assembly mounted on the mandrel, said assembly including a stationary unit and a movable unit, said movable unit being arranged to be displaced vertically out of horizontal alignment with the stationary unit to permit the well fluid to freely by-pass the assembly on the downstroke of the swab, the movable unit being arranged to move back into horizontal alignment with the stationary member and to be distorted into packing position with said stationary member upon the upstroke of the swab, and co-acting grooves and ribs on the mandrel and units for retaining the units in place on said mandrel, and for guiding the movable unit in its movement.

7. A well swab including, a mandrel having vertical grooves therein, a packing assembly mounted on the mandrel and including a pair of units which are arranged to be displaced out of horizontal alignment with each other to permit the well fluid to freely by-pass the assembly on the downstroke of the swab, each unit comprising an elastic packing member substantially semi-circular in cross-section so as to fit around the mandrel, confining elements at each end of the member for holding said member therebetween, and means on said elements for engaging the grooves of the mandrel for retaining the units on said mandrel.

8. A well swab including, a mandrel having vertical grooves therein, a packing assembly mounted on the mandrel and including a pair of units which are arranged to be displaced out of horizontal alignment with each other to permit the fluid to freely by-pass the assembly on the downstroke of the swab, each unit comprising an elastic packing member substantially semi-circular in cross-section so as to fit around the mandrel, confining elements at each end of the member for holding said member therebetween, means on said elements for engaging the grooves of the mandrel and for guiding the movable unit in its movement, and means for limiting the distortion of the packing members.

9. A well swab including, a single longitudinal supporting member, an elongate packing assembly mounted on the member and including a stationary unit and a movable unit, said movable unit being arranged to be displaced longitudinally out of registration with the stationary unit, and longitudinal means on the single member co-acting with the stationary unit to hold said unit on said member, said means also co-acting with the movable unit for retaining said unit on the member and for guiding the same in its longitudinal movement.

10. As a sub-combination in a well swab, a packing assembly including, a grooved support,

a split sealing element, and split top and bottom caps therefor, said caps having vertical ribs for engaging the grooved support to retain said assembly on said support.

11. As a sub-combination in a well swab, a packing assembly including, a grooved support, a split sealing element, and split top and bottom caps therefor, said caps having means for engaging the grooved support to retain said assembly on said support.

12. As a sub-combination in a well swab, a sealing assembly including, a recessed support, a pair of upper confining members each semi-circular in cross-section, a pair of lower confining members of semi-circular cross-section, and a pair of elastic packing elements confined between the upper and lower members, said packing elements also being semi-circular in cross-section, each confining member having vertical ribs extending substantially throughout its length at its longitudinal extremities and arranged to coact with a recessed support to retain the assembly on said support.

13. As a sub-combination in a well swab, a single supporting mandrel having diametrically opposed grooves extending substantially throughout its length, each groove having one end enlarged in transverse width whereby the enlarged portion is substantially twice the width of the remainder of the groove.

14. A well swab including, a mandrel, a swab element surrounding the mandrel and including a plurality of registering sections having elastic deformable members arranged to be deformed by the liquid lifted when in registration with each other, one of said sections being immovable on said mandrel and the other section being slideable longitudinally on said mandrel from the first section to provide a free by-pass for liquid between said sections, whereby the swab may be quickly lowered in a body of liquid in a well, longitudinal guide means formed on the periphery of said mandrel, and means on the movable section of the element co-acting with said guide means to retain said movable section in registering position and for guiding said section into registration with the stationary section.

15. A well swab including, an elongate supporting member having abutments remotely spaced apart, a packing element mounted on the supporting member and including two sections which in one position are in registry and, one of which is stationary on said member and the other of which is slideable longitudinally between the abutments thereof, the stationary section engaging one of the abutments of the member, and the slideable section engaging the other abutment, whereby its displacement from the other section is limited, and interlocking means between the supporting member and the slideable section of the packing element for retaining said section thereon and against rotation.

16. A well swab including, a mandrel, a swab element surrounding the mandrel and having a displaceable section movable longitudinally approximately its entire length on the mandrel, and means formed on the periphery of said mandrel for guiding the section longitudinally thereof.

17. A well swab including, a single longitudinal supporting member, a packing assembly mounted on the member and including a pair of units, one of which is arranged to be displaced out of horizontal alignment with the other, the supporting member having longitudinal guide means of greater length than either of said

- units formed on the periphery of the member, and means on the movable unit for engaging said guide means, whereby said unit is held in longitudinal alinement when displaced.
- 5 18. A well swab including a single supporting mandrel, a packing assembly carried by said mandrel, and including a pair of units, one of which is slidable longitudinally of the mandrel relative to the other unit of said pair, and means 10 to mount the slidable unit on the mandrel, thereby to derive sole support from the latter, comprising guide means formed on the periphery of the mandrel, and complementary guide means 15 on the slidable unit engaging the guide means of said mandrel to hold the slidable unit against rotation.
19. A well swab in accordance with claim 18, wherein the guide means on the mandrel consists of a pair of grooves extending longitudinally of 20 the mandrel and located on opposite sides thereof, to form projections, and wherein the complementary guide means have recesses receiving the projections and portions extending into the grooves.
20. A well swab including a single supporting rod, a packing assembly carried by said rod and including a pair of units one of which is movable longitudinally away from the other, said rod having an irregular cross-section, which constitutes its periphery, so as to hold said movable unit against rotation while permitting longitudinal movement thereof, and means carried by the movable unit and engaging the periphery of the rod to mount the movable unit on the rod. 10
21. A well swab including a single supporting rod, a packing assembly including a pair of units carried by said rod, one of which is slidable longitudinally of the rod relative to the other unit of said pair of units, and means to mount the 15 slidable unit on the rod thereby to derive sole support therefrom, comprising complementary interlocking means between the rod and the slidable unit, and one of which means is on the periphery of the rod, whereby to hold the units 20 against relative rotative movement while providing for sliding of said slidable unit on the rod.

BENJAMIN E. PARRISH.
